UNITED STATES PATENT OFFICE.

A. K. EATON, OF NEW YORK, N. Y.

MACHINE FOR PULVERIZING ORES.

Specification of Letters Patent No. 10,567, dated February 28, 1854.

To all whom it may concern:

Be it known I, A. K. EATON, of the city, county, and State of New York, have invented certain new and useful Improvements in Machinery for Pulverizing Ores and Which Are Also Applicable to other Purposes, of which the following is a full, clear, and exact description, reference being had to the accompanying drawings, in 10 which—

Figure 1 represents a view in perspective of one of the many forms in which my improved pulverizer may be constructed; Fig. 2 a side elevation of the same, showing in 15 vertical section the pulverizing apparatus.

My improved pulverizer combines the functions of the mortar and mill-stone in such manner as to render the thorough and fine pulverizing of the former compatible 20 with the rapid and even working of the latter, whereby the work is done more thoroughly and with greater speed and economy of power than has heretofore been attained.

The accompanying drawings represent a 25 strong frame (A), in which a spindle (B), is supported in suitable bearings. This spindle is rotated in this example by means of a wheel (a), secured upon its lower end and which gears into another wheel (b), on 30 the driving shaft (c), which may be driven by any convenient prime mover. On the middle of the spindle (B), a pulley (d), is mounted which transmits motion through a belt to a similar pulley (e), which gives motion to a counter shaft (D), on which the 35 pulley is mounted. To the upper extremity of the spindle (B), a shallow mortar or grinding dish is secured, which while the machine is in operation rotates constantly.

The upper surface of this dish is a segment 40 of the concave surface of a hollow sphere, whose center is the middle (i), of an inverted step (n), secured to the underside of the upper bar of the frame. This step consists of a tubular flanged case (E) in the 45 lower end of which the bearing slides, the upper end being fitted with a screw follower (F), which may be turned up or down to bear less or more upon a spring (s), inverted between the step and follower to 50 regulate the pressure of the step downward for a purpose to be hereafter described, and also to permit it to yield. A thick-rubber (G), rests upon and is fitted to the concave 55 surface of the revolving mortar (H). From the center of this rubber a stem (I), extends

up to the step (n), into which its upper extremity is loosely fitted. The lower extremity of this stem with its rubber (G), is free to vibrate within the revolving dish, 60 which is about double the diameter of the oscillating rubber, and since the radius and center of oscillation of the rubber (G), coincide with the radius and center of curvature of the grinding surface of the mortar, it is 65 plain that the under surface of the rubber, and upper surface of the mortar will always fit together properly, notwithstanding the traversing of the one across the other.

The lower end of the stem (I), is connected by a link rod (J), with a crank pin (K), on the upper extremity of the shaft (D). The throw of this crank is such that the vibrations of the rubber (G), will not carry its periphery beyond the inner side 70 of the flange (L), of the rotating dish. The rubber (G), must be guided in its oscillation so as to prevent it from being carried around by the dish. In this example this is effected by the stem (I), passing through a 75 slot (N), in the cross bar (P), of the frame. The dish (H), and the rubber (G), are made to press against each other with a variable force during the operation of 80 grinding as the nature of the work may require by adjusting the follower (F), of the step; and in case of any hard substance which the rubber cannot crush getting between them, the step spring (s) will permit 85 the yielding or separation of the rubber 90 from the dish to protect them from breakage.

The adjacent or grinding surfaces of the 95 vibrating rubber and rotating dish may be indented, grooved, or roughened, or have 100 cavities formed in them in any way the judgment of the constructor may deem expedient, or special circumstances show to be necessary; and in case grinding and amalgamation are conducted together as they 105 may be whenever it is thought advisable, a cavity in the center of the dish (H), surrounded by several other cavities, with 110 grooves connecting them should be made, or some other equivalent device adopted, in order to receive the mercury, and facilitate its contact with the ore. If it should be deemed advisable the rubber (G), can be made to revolve as well as to oscillate by simply mounting a pulley upon the stem, 115 and connecting the shackle bar (J), to a sleeve on the stem (I), which will permit

the stem to rotate freely, at the same time that it will as effectually oscillate it as it now does. The rim (L), of the dish (H), may be made removable to facilitate repairs, 5 or the removal of the rubber (G).

What I claim as my invention and desire to secure by Letters Patent is—

A rotating dish or mortar to hold the ore to be puerized, and the water, mercury, or 10 other liquids with which it may be advisable

to mix the same, in combination with a vibrating rubber, or pestle which is made to traverse the bottom of the mortar, substantially as herein set forth.

In testimony whereof, I have hereunto 15 subscribed my name.

A. K. EATON.
